(57) **CLAIM**

I claim the ornamental design for stacked golf balls and golf tees secured by transparent film to a flat base, as shown and described.

DESCRIPTION

FIG. 1 is a perspective view of stacked golf balls and golf tees secured by transparent film to a flat base.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

In the drawings, the broken lines shown in the figures depict unclaimed subject matter and form no part of the claimed design.

1 Claim, 7 Drawing Sheets
